UNITED STATES PATENT OFFICE

FRANK W. FULLER, OF ST. PAUL, MINNESOTA

REVERSIBLE RADIATOR HANGER

Application filed December 3, 1926. Serial No. 152,344.

The present invention relates to a radiator hanger.

In the hanging of a radiator from a wall it is customary to use a bracket fastened to a wall against which the radiator is to be hung and having a foot portion suspended by a pipe connected to said bracket, the foot portion passing beneath the lower end of the radiator to support it.

It is necessary in order to make the radiator hang vertically in outwardly spaced relation from the wall to provide spacing members at both the upper and lower ends thereof, and, since the distance which it is desired to space the radiator from the wall varies with different installations it is usually necessary to carry a large number of spacing members and brackets in stock in order to provide hangers for the various installations required.

An object of the present invention is to hang a radiator from a wall by a hanger having an adjustable top bracket and spacing member and an adjustable bottom spacing member to space a radiator from a wall at a distance which may vary with the requirements of the individual installation.

In order to attain this object, there is provided, in accordance with one feature of the invention, a radiator hanger with a reversible top bracket having side portions of different lengths to space the top of a radiator supported thereby outwardly from the wall, an adjustable foot member being also provided to space the lower portion of a radiator supported thereby outwardly from the wall at varying distances which are determined by the position of the foot member with respect to the wall.

These and other features of the invention, not specifically mentioned, will be more fully brought out in the following description and the accompanying drawings, wherein:

Figure 1, shows a transverse section through a radiator supported against a wall where no baseboard is used and where it is desired to have the radiator positioned closely adjacent the wall.

Figure 2, is a view similar to Figure 1, showing the radiator spaced outwardly from the wall a greater distance than that illus-

trated in Figure 1, with the foot member supported on a baseboard.

Figures 3, 4, and 5, show, respectively, a top elevation, side elevation, and cross section of the adjustable foot member.

Figure 6, is a view in perspective of a reversible top supporting bracket.

Figure 7, is a view in front elevation of the complete hanger showing a radiator supported thereon in dotted lines.

Figure 8, is a view in top elevation of a radiator supporting arm.

Figure 9, is a view in side elevation thereof; and

Figure 10, is a view on the line 10—10 of Figure 9.

Referring to the drawings in detail, a wall bracket A is constructed to have the two sides 1 and 2 thereof of unequal length, the side 1 being of the length required when it is desired to hang the radiator closely adjacent the wall, as in Figure 1, and the side 2 being somewhat longer so as to space the radiator further from the wall, as in Figure 2. It is customary to hang the radiator close to the wall when the conservation of space is desired, the normal spacing in this case being about one and seven-eighths inches and to hang the radiator further from the wall where the conservation of space is not a factor or where sanitation is the main factor to be considered as in hospitals and public buildings. In such installations the standard spacing is two and one-half inches from the wall.

Holes 3 in the side 1, and holes 4 in the side 2, may be used reversibly for receiving a lag screw 5 set in a wall 6 by means of which the wall bracket A is fastened to the wall, or to receive pipe 7 upon which an arm 8 is mounted to support a radiator B. The holes 3 and 4 are each provided with a small offset portion 9 having a radius of curvature equal to that of the lag screw, the large central portion of said holes being of a size to freely receive a stay bolt 14, which is passed between the columns of the radiator and is provided with a large washer 15 on the outer end thereof to engage the inner edges of two adjacent radiator sections to hold them tightly against the wall.

the flange 10 or 11, as required, to provide the required spacing from the wall. The pipe 7 is cut to the required length for each radiator as it is installed and is threaded to receive a base spacing member C thereon. The base member C comprises a flat, central portion 16, with downwardly turned end portions 17 and 18 across the narrow dimension of the foot member C to provide increased supporting area against the wall or baseboard against which this base member rests. An opening 19 is provided in the foot member C which may be threaded to engage the lower end of the pipe 7, the center of the opening being spaced at predetermined distances from the sides of the foot member C. The greatest distance from the center of the opening 19 to any side of the foot member C is that on the line 20. This long dimension is required when it is desired to hang the radiator with the foot member C resting against the wall and with the radiator spaced outwardly from the wall the maximum distance. In standard practice this maximum dimension is about two and one-half inches. The other three sides of the foot member C are at distances from the center of the opening which will permit the radiator to be hung vertically either when positioned close to the wall, as in Figure 1, where no baseboard is employed, or with the radiator spaced outwardly a greater distance either with the foot member resting upon the baseboard or with the long end 20 resting against the wall, not shown. The standard minimum wall clearance which is provided when the radiator is hung as in Figure 1 is about one and seven-eighths of an inch, while the maximum is about two and one-half inches. The other two sides of the foot spacing member may be employed to compensate for variations in the thickness of baseboards encountered, since some baseboards are five-eighths of an inch thick, some three-quarters of an inch, and some seven-eighths of an inch. The smallest dimension may be used when the radiator is supported as in Figure 2 with a seven-eighths of an inch baseboard. The second smallest dimension may be used where a baseboard three-quarters of an inch thick is encountered, and the third smallest dimension may be used where a baseboard five-eighths of an inch thick is encountered. While the foot member C is shown as threaded onto the pipe 7, the opening 19 in the foot member may be of a size to freely receive the pipe, and a nut, not shown, similar to a nut 21 on the upper end of the pipe 7 may be employed to sustain the weight of the radiator and retain the foot member on the pipe. A radiator supporting arm comprises a rear portion 22 having an opening therethrough of a size to receive the pipe 7 and an arm portion 23 having an upwardly curved outer end to support the lower end of the radiator thereon. The radiator

supporting arm 8 is here shown as being formed from heavy sheet metal with the rear end thereof looped around to receive the pipe 7 and being spot welded as at 24 and 25 to provide additional strength. While this is the preferred form, the radiator supporting arm 8 may be of cast or forged metal of substantially the shape shown without departing from the spirit of the invention.

In hanging a radiator on a wall in accordance with the present invention, a lag screw 5 is first firmly affixed in position on the wall and the bracket A is hung upon the lag screw. The pipe 7 is then cut to the required length and threaded at both ends. The nut 21 at the upper end thereof is then screwed onto the pipe and the pipe is dropped through an opening 3 or 4 in the wall bracket A. The bracket A is positioned with either side 1 or 2 adjacent the wall and with the other side 2 or 1 extending outwardly therefrom, depending upon whether the radiator is to be hung close to the wall or spaced outwardly therefrom to provide additional clearance. The radiator supporting arm 8 is then placed in position upon the pipe and the foot member C is secured in position on the lower end of the pipe, and is adjusted to provide the proper clearance from the wall or baseboard. The lower end of the radiator is then placed upon the radiator support arm and the radiator is tilted up into position. The tie bolt 14 with a washer 15 thereon is then inserted between the columns of the radiator and the end of the tie bolt is passed through the slot 12 or 13 in the upturned flange 10 or 11. A nut is then threaded onto the inner end of the tie bolt, and the tie bolt screwed into the nut, using a screw driver introduced between the sections of the radiator to engage the slotted head of the tie bolt. This faces the radiator inwardly into close abutment with the upturned flange 10 or 11 and completes the operation.

With a radiator hanger of the present type it is unnecessary to stock different sizes of brackets and foot members or radiator support arms to provide different spacings from the wall, since the hanger is adaptable for any standard size or type of radiator and to provide a required spacing from the wall or baseboard.

I claim:

1. A wall radiator hanger, comprising a bracket securely fastened to a wall, a supporting member carried by said wall bracket to depend therefrom, a foot piece mounted upon said supporting member to support a radiator thereon, and a spacing member mounted upon the lower portion of said supporting member below said foot piece to be rotatable thereon and to provide a support for the latter, said spacing member having the sides thereof at different distances from the supporting member to space the lower portion of

said supporting member a predetermined distance from a wall upon which the device is mounted.

2. In combination with a wall radiator hanger having a depending support member carried by a wall bracket and a foot piece mounted on said depending member to carry a radiator, a combined bottom nut and base spacing member positioned below said foot piece, comprising a substantially rectangular member having a hole drilled and tapped therein of a size to threadedly engage the lower end of said depending member, said hole being so disposed as to be spaced at different distances from the sides of said base spacing member.

3. In combination with a wall radiator hanger having a depending support member carried by a wall bracket, a foot piece mounted on said depending member to carry a radiator, and a combined stop and base spacing member positioned below said foot whereby to limit the downward movement of the latter and to hold the lower portion of the radiator spaced from a wall.

In testimony whereof I affix my signature.
FRANK W. FULLER.
